US0D1049064S

(12) **United States Design Patent** (10) **Patent No.:** **US D1,049,064 S**
(45) **Date of Patent:** **** Oct. 29, 2024**

(54) **HEAT SINK COVER**

(71) Applicant: **MARVELL ASIA PTE, LTD.**,
Singapore (SG)

(72) Inventors: **Chris Togami**, Santa Clara, CA (US);
Radhakrishnan L. Nagarajan, Santa
Clara, CA (US); **Gary Sasser**, Santa
Clara, CA (US); **Brian Taylor**, Santa
Clara, CA (US)

(73) Assignee: **MARVELL ASIA PTE LTD.**,
Singapore (SG)

(**) Term: **15 Years**

(21) Appl. No.: **29/811,314**

(22) Filed: **Oct. 13, 2021**

(57) **CLAIM**

The ornamental design for a heat sink cover as shown and described.

DESCRIPTION

FIG. 1 shows a perspective view of a heat sink cover according to the new design.

FIG. 2 is a top plane view of the heat sink cover of FIG. 1. FIG. 3 is a bottom plane view of the heat sink cover of FIG. 1.

FIG. 4 is a left side elevational view of the heat sink cover of FIG. 1.

FIG. 5 is a right side elevational view of the heat sink cover of FIG. 1.

FIG. 6 is a front side elevational view of the heat sink cover of FIG. 1; and,

FIG. 7 is a back side elevational view of the heat sink cover of FIG. 1.

1 Claim, 5 Drawing Sheets
